MOTOR-DRIVEN TUNING CONTROL FOR RADIO RECEIVERS

Filed June 20, 1947

UNITED STATES PATENT OFFICE

2,490,591

MOTOR-DRIVEN TUNING CONTROL FOR
RADIO RECEIVERSFrank Himmer, Philadelphia, Pa., assignor to
Philco Corporation, Philadelphia, Pa., a cor-
poration of Pennsylvania

Application June 20, 1947, Serial No. 755,881

2 Claims. (Cl. 250—36)

1

The invention herein described and claimed relates of a tuning system for radio communication apparatus, and in particular to an improved tuning system for superheterodyne radio receivers.

While the components comprising the new tuning system may all be placed at the same location, and, if desired, may all be contained in a single housing, the improved system may be most advantageously employed for controlling the tuning of a superheterodyne radio receiver from a remote location. Wire or cable connections are employed between the receiver and the remote control point, but no mechanical connection is required. The invention may consequently be employed, to considerable advantage, in radio receiving apparatus intended for installation in automobiles, airplanes, motorboats, and other form of mobile craft since, in mobile installations, it is frequently desirable to mount tuning-control means for the radio receiver on or near the instrument or driving-control panel while the radio receiver is desirably placed elsewhere in the vehicle or craft.

In accordance with a preferred embodiment of the invention, improved means are provided for automatically tuning the local oscillator of the receiver to the resonant frequency of a tuned or frequency-selection circuit located at a remote control position and their selected by the operator. The operator may make the selection automatically by depressing a station-selector pushbutton; or the selection may be made manually at the remote location by depressing a "Manual" pushbutton and adjusting a manual-tuning control knob to the desired position, as shown by a manual-tuning indicator dial. The tuner of the receiver is motor driven by a suitable electric motor, located, if desired, within the housing of the radio receiver. In the receiver illustrated in the drawing, the tuner is comprised conventionally of the variable inductances of the tunable circuits of the R.-F. amplifier, mixer, and local oscillator stages of the receiver. A portion of the output of the local oscillator is applied, by way of a shielded or other suitable conductor, to the remotely-located tuned circuit selected by the operator; and the voltage developed across a portion of the selected remote tuned circuit is detected, fed back to the receiver as a control signal, and utilized to control the operation of the tuner motordrive.

It is an object of this invention to provide, for a superheterodyne radio receiver, an improved

2

tuning system which includes tuning-control means adapted to be coupled to the receiver by electrical connections, without necessity of mechanical linkage.

5 It is another object of this invention to provide a superheterodyne radio receiver, capable of being controlled from a remote location, by station-selector pushbutton, and/or manual, tuning means, without employment of mechanical coupling between the remote tuning-control means and the radio receiver.

10 It is a further object of this invention to provide, for a superheterodyne radio receiver, improved means for automatically tuning the frequency of the local oscillator of the receiver to substantially the resonant frequency of a tuned circuit located in a remote tuning-control position and there selected by the operator by either pushbutton, or manual, tuning means.

15 20 These and other objects, features and advantages of the present invention will become clear from a consideration of the following detailed description of a preferred embodiment illustrated in the single figure of drawing.

25 Referring now to the drawing, there is schematically represented a superheterodyne radio receiver 10 including an R.-F. amplifier 11, a frequency converter 12 comprised of a mixer section 13 and a local-oscillator section 14, an I.-F. amplifier 15, a second detector, AFC circuit, and first audio amplifier 16, a push-pull audio-frequency power amplifier 17, and a loudspeaker 18. The local oscillator 14 is represented schematically as being comprised, conventionally, of a section of a pentagrid-converter tube, an oscillator-plate voltage dropping resistor 21, a bypass capacitor 22, a grid leak 23, a grid capacitor 24, and a tunable network 25 consisting of variable inductance 26 and capacitor 27. All of the components mentioned thus far are conventional and require no further description, either with respect to structure or manner of operation.

30 35 40 45 50 55 In accordance with the present invention, for purposes that will become clear, means are provided for deriving, from local oscillator 14, a portion of the R.-F. oscillator voltage appearing across tuned circuit 25. Means are also provided for deriving, from the said oscillator, the unidirectional voltage developed across grid leak 23. Various means may be employed for these purposes; the means shown in the drawing, and about to be described, merely constitute the preferred manner of accomplishing the derivations. In the illustration, a portion of the R.-F. oscil-

lator voltage is derived by means of pickup coil 28 mutually coupled to oscillator coil 26; capacitor 79 provides an A.-C. ground connection for the low-potential end of the pickup coil. In the illustration, the unidirectional voltage is derived by way of an isolation or filter circuit 29, comprising series resistors 30, 31 and shunt capacitor 32. Resistor 30 isolates capacitor 32 from the oscillator; and resistor 31 isolates capacitor 32 from pickup coil 28.

In accordance with the present invention, receiver 16 also includes a tuner motor 33, a tuner-motor control tube 34, a tuner-motor control relay 35, a reversing-switch selector relay 36, a tuner-actuated motor-reversing switch 37, and a tuner-actuated manual-tuning correcting switch 38. The functions of these components will become clear as the description proceeds.

The plate of tuner-motor control tube 34 is shown to be connected to a source of positive potential, B+, through coil 39 of tuner-motor control relay 35. The cathode of control tube 34 is connected to ground through resistor 78, and is also connected to the cathode-biasing network 40 of push-pull amplifier 17. The grid of tube 34 is also connected to the push-pull amplifier biasing network 40, but is connected by way of resistor 75 of the remote tuning-control unit 60. The remote tuning-control unit will be described hereinafter.

Tuner-motor control relay 35 is a double-pole double-throw relay comprising a coil 39 and two double-throw switches 41 and 42.

Tuner motor 33 is a reversible, shunt wound, D.-C. motor comprising an armature 46 and a center-tapped shunt-field winding 47. The motor is mechanically coupled, through a magnetic clutch 44 and through suitable reduction gearing (not shown), to the receiver tuner comprised, conventionally, of the variable inductances 19, 20 and 26 of the tunable circuits of R.-F. amplifier 11, mixer section 13 and local oscillator section 14, respectively. In the drawing, the mechanical coupling between the three-unit tuner and motor 33 is indicated by the dotted-line representation 45.

The reversing-switch selector relay 36 is a three-pole double-throw relay comprising a coil 48 and three double-throw switches 49, 50 and 51.

Variable inductances 19, 20 and 26 are ganged and may comprise an integral multi-unit tuner structure having three coils mounted, conventionally, in parallel axial relation to each other. Each coil has a core of iron or other suitable material, usually a powdered core of high magnetic permeability, and the three cores are moved simultaneously, as by a common screw or cam arrangement. In the illustrated receiver, the multi-unit tuner structure includes a switch 37, preferably of the "over-center" type, and a normally-open switch 38; both switches are shown schematically in the upper right-hand portion of the drawing. These switches are so mounted on the tuner as to be actuated by actuating-arms 52, 54 or 53, 55 when the cores of the tuner reach either limit of the core stroke. Suitable physical switch structures will immediately be apparent from the simplified drawing, and inasmuch as the structural arrangement does not constitute, per se, the present invention, it is deemed sufficient to illustrate schematically the manner in which switches 37 and 38 operate.

It will be assumed that actuating-arms 52, 53, 54 and 55 are moved to the right, in the drawing, when the tuner cores are moved in a

frequency-increasing direction, and that the actuating-arms are moved to the left when the tuner cores are moved in a frequency-decreasing direction. The actuating-arms may conveniently be so positioned that as the tuner cores reach the high-frequency limit of the core stroke, actuating-arms 52 and 54 come into engagement with the movable contact-arms of switches 37 and 38, respectively, to move the switch arms to their right-hand positions; and as the tuner cores reach the low-frequency limit of the core stroke, the movable contact-arms of switches 37 and 38 are engaged by actuating-arms 53 and 55, respectively, and the switch arms are moved to their left-hand positions.

After the contact-arm of switch 37 has been moved to the right-hand position, at the high-frequency limit of the core stroke, the arm remains in the right-hand position until engaged by actuating-arm 53 and moved to the left-hand position at the low-frequency limit of the stroke; it then remains in the left-hand position until moved. But the movable contact-arm of switch 38 makes but momentary closed contact at both the high-frequency and low-frequency limits of the stroke, being returned to a normally open position by spring S.

The means by which the tuning of receiver 16 may be controlled from a remote location without employment of mechanical linkage between the receiver and the remote control point will now be described.

In the drawing, there is shown a tuning-control unit 60 comprising seven mechanically interlocking pushbuttons, 1-7. Pushbuttons 1-5 are used to select automatically preselected stations. Pushbutton 6 is the "Manual" button and is depressed when manual tuning is to be employed. Pushbutton 7 is the "Off" button and is depressed when it is desired to turn off the receiver. In the illustrated tuning-control unit, there is no "On" pushbutton, and depressing any one of pushbuttons 1-6 turns on the receiver. The tuning-control unit 60 is shown to be connected to receiver 16 by means of a shielded conductor 71 and a six-conductor cable 76; all seven conductors may be under a common sheath, if desired.

Associated with station-selector pushbuttons 1-5 are adjustable inductance elements, 61-65; and associated with "Manual" pushbutton 6 is a manually variable inductance element 66 operatively connected to a manual-tuning control knob (not shown) and to a manual-tuning indicator 55 or dial 68. The manual-tuning control knob is mechanically coupled to a manually-operated reversing switch 69 through a frictional clutch (not shown) so that when the control knob is initially moved in a given direction, the movable contact-arm of reversing switch 69 moves in the same direction. For example, when the manual-tuning control knob is first turned in a clockwise direction, the arm of reversing switch 69 is moved to the right-hand position. Further clockwise rotation of the control knob does not affect the position of the switch arm, but when the control knob is turned in the reverse direction, i. e., counterclockwise, the contact-arm of switch 69 immediately moves to the left-hand position.

The "Off" pushbutton 7 is connected in conventional manner between the filament and power supply circuits of the radio receiver 16 and a source of external A.-C. or D.-C. voltage 70. In the case of an automobile radio, voltage source

70 may conveniently be a six-volt storage battery, as illustrated in the drawing.

In the drawing, pushbuttons 1-5 are double make-contact switches; pushbutton 6 is a double make-and-break contact switch; and pushbutton 7 is a double break-contact switch. One make-contact of each of pushbuttons 1-6 is connected, by way of shielded conductor 71, to pickup coil 28 of local oscillator 14. The other make-contact of each of pushbuttons 1-6 is connected, by way of one of the adjustable inductances 61-66, associated with the particular pushbutton, to the grid of a plate-detector triode 72 which, together with grid capacitor 73, filter capacitor 74 and plate resistor 75, connected as shown, is included within the housing of tuning-control unit 60. The plate-circuit leads of tube 72, the leads from the fixed contacts of reversing switch 69, a lead from one of the break-contacts of pushbutton 6, and a lead from "Off" pushbutton 7, go to the radio receiver 10 and are shown to be placed in a common cable 76.

The operation of the improved tuning-control means of the present invention will now be described.

To make the operation of the improved tuning system more readily understood, various operating conditions will be assumed in sequence. It will be assumed first that, as the description starts, the receiver shown in the drawing is not operating, having been turned off in the manner provided, namely, by depressing the "Off" pushbutton 7. Control relays 35 and 36 are therefore shown in de-energized positions.

Assume now that station-selector pushbutton 2 is pressed to tune in automatically a station having a carrier frequency of say 650 kc. When pushbutton 2 is pressed, the "Off" pushbutton 7 is released since, in the receiver illustrated, all seven pushbuttons are mechanically interlocking (not shown) and only one of the pushbuttons is maintained in depressed position at a time. Assume that before pushbutton 2 is pressed, the receiver, altho not turned on, is tuned to say 550 kc., which is lower than the frequency of the station associated with station-selector pushbutton 2.

In the situation described above, when the receiver is turned on by depressing pushbutton 2, plate-detector tube 72, in the remote tuning-control unit 60, remains non-conductive, being biased beyond cut-off by the application to its grid of the negative D.-C. voltage developed across grid leak 23 of the receiver's local oscillator 14. The voltage developed across grid leak 23 at receiver 10 is applied to the grid of detector tube 72 at control unit 60, by way of isolating or filter circuit 29 located at the receiver 10, shielded conductor 71 connecting receiver 10 to control unit 60, the closed contacts of pushbutton 2, and inductance 62 associated therewith.

When, as has just been described, detector tube 72 is biased beyond cut-off and is non-conducting, control tube 34 at receiver 10 conducts by reason of having a zero bias applied thereto. The bias voltage on control tube 34 is zero due to the fact that the unidirectional voltage appearing across biasing network 40 of the push-pull amplifier 17 is applied both to the grid and to the cathode of tube 34. Plate current of control tube 34 flows through coil 39 of control relay 35, causing the movable contact-arms of switches 41 and 42 of relay 35 to move to the upper-contact positions. When this occurs, current from voltage-source 70 flows through coil 48 of relay 36 by way of the

closed contacts of "Off" pushbutton 7, the upper contact of switch 42 of relay 35, and the lower contacts of "Manual" pushbutton 6. The movable contact-arms of switches 49, 50 and 51 of relay 36 then move to the upper-contact positions. With the contact arms of switches 49 and 50 in the upper positions, a circuit is completed, either through the upper or lower portion of the center-tapped field winding 47, depending upon whether the movable contact-arm of switch 37 is in the left-hand or right-hand position. Assume, for the purpose of the example now being described, that the arm of switch 37 is in the left-hand position; current then flows through the upper portion of field winding 47. Assume further that, when current flows through the upper portion of field winding 47, motor 33 rotates in a direction to move the three cores of the multi-unit tuner in a frequency-increasing direction, it being understood that the direction of rotation of reversible motor 33 is determined by whether the current flows through the upper or lower section of field winding. Then, in the example now being described, it will be seen that, when pushbutton 2 is pressed, the motor-driven tuner moves in a direction to increase the frequency of the R.-F. mixer and local oscillator stages. A portion of the oscillator R.-F. voltage is picked up by pick-up coil 28 and applied, by way of shielded conductor 71, across the series-tuned circuit 62, 73 associated with the depressed station-selector pushbutton; and the R.-F. voltage thus appearing across capacitor 73 is applied to the grid of plate-detector tube 72. In the present example, motor 33 continues to rotate in the frequency-increasing direction until the frequency of local oscillator 14 coincides substantially with the frequency of the series-tuned circuit 62, 73 associated with depressed pushbutton 2. The circuit constants are so chosen that when the frequency of local oscillator 14 reaches substantially the resonant frequency of the selected series-tuned circuit, in the present example, the tuned circuit associated with depressed pushbutton 2, the peaks of the R.-F. voltage on the grid of tube 72 rise above cut-off and tube 72 conducts. When tube 72 conducts, the voltage developed across resistor 75 in the plate circuit of tube 72 is sufficient to bias control tube 34 below cut-off and tube 34 ceases to conduct. Control relay 35 thereupon becomes de-energized and the movable contact-arms of switches 41 and 42 return to the de-energized positions, i. e., to the lower contacts. By reason of the opening of switch 42, magnetic clutch 44 disengages, motor 33 stops running, relay 36 is de-energized, and the contact arms of relay 36 return to the lower-contact positions. The receiver is now tuned, well within the range of conventional automatic-frequency-control (AFC), to the frequency of the station associated with station-selector pushbutton 2; and the receiver is also in condition to respond to the succeeding action of the operator, whatever that might be.

Although the use of automatic-frequency-control (AFC) is not essential to the improved system, the illustrated embodiment does employ AFC and is so arranged that when motor 33 is running, the AFC voltage developed, in customary manner, in block 16 is shorted to ground through the upper contact of switch 41 of control relay 35. When the frequency of local oscillator 14 reaches substantially the resonant frequency of the selected series-tuned circuit and tube 34 stops conducting and control relay 35 is de-energized and motor 33 stops running, the automatic-fre-

frequency-control (AFC) system of the receiver is restored to operative condition by the removal of the ground connection at switch 41.

Assume that the operator next presses station-selector pushbutton 5, thus releasing pushbutton 2. The frequency of the station of pushbutton 5 is, say 1500 kc., which is higher than that of the station of pushbutton 2. When pushbutton 5 is pressed, the frequency of local oscillator 14 no longer coincides with the resonant frequency of the selected series-tuned circuit and the peak amplitude of the R.-F. voltage appearing on the grid of tube 72 is below cut-off; tube 72 therefore ceases to conduct. The bias on control tube 34 thereupon returns to zero, and control tube 34 conducts. Control relay 35 is then energized, and the closing of switch 42 completes the circuit through armature 46, the upper portion of field winding 47, the upper-contact of switch 49 and the left-hand contact of switch 37. Motor 33 therefore turns in a direction to increase the frequency of local oscillator 14. Motor 33 continues to turn in a frequency-increasing direction until the frequency of oscillator 14 is substantially the resonant frequency of the series-tuned circuit 65, 73 associated with station-selector pushbutton 5.

Assume that the operator next presses station-selector pushbutton 4. It is being assumed throughout this description that the station-selector pushbuttons are in conventional sequential order, i. e., that the frequency of the station associated with pushbutton 1 is lowest and that the frequency of the stations associated with pushbuttons 2, 3, 4 and 5 are higher in sequential order. The frequency of the station of pushbutton 4 is say 1400 kc. In the present example, at the time pushbutton 4 is pressed, the contact-arm of switch 37 is in the left-hand position, i. e. the position assumed in the preceding examples. As indicated previously, the direction of rotation of motor 33, during station-selector pushbutton operation, is determined by the position of the contact-arm of switch 37. With the contact-arm in the left-hand position, current flows through the upper portion of field winding 47 and motor 33 rotates in a direction to increase the frequency of local oscillator 14. In the example now being described, the frequency of oscillator 14, at the time pushbutton 4 was pressed, was, however, higher than the resonant frequency of the tuned circuit associated with pushbutton 4, and a lower, not higher, oscillator frequency is wanted. Motor 33 continues to rotate in the frequency-increasing direction until the cores of the multi-unit turner reach the upper-frequency limit of the core stroke, corresponding to a station frequency of say 1700 kc. As the tuner cores reach the upper-frequency limit, actuating-arms 52 and 54 engage switches 37 and 38, respectively, and the contact-arms are moved to the right-hand contact positions, as viewed in the drawing. Switch 38 has no function in the operation now being described, but the movement of the contact-arm of over-center switch 37 from the left-hand to the right-hand position, opens the circuit through the upper portion of field winding 47 and closes the circuit through the lower portion of the field winding. This reverses the direction of rotation of motor 33, and the tuner cores are now moved in a direction to decrease the frequency of the tuned circuits of the R.-F. amplifier, mixer and local oscillator stages of the receiver. Motor 33 continues to rotate in the frequency-decreasing direction until the frequency delivered by the local oscillator

is substantially the resonant frequency of the series-tuned circuit, comprising inductance 64 and capacitor 73, associated with station-selector pushbutton 4. At that time, tube 72 conducts, and control tube 34 ceases to conduct, thereby stopping the tuner at the desired point, in the manner previously described.

Assume that the operator now desires to manually tune in a station not appearing on the station-selector pushbuttons. Assume that the frequency of the station desired is 900 kc. and that the indicator hand of dial 68, associated with manual-tuning pushbutton 6, points to 550 kc., showing that the frequency of the station last manually selected was 550 kc. It will be understood that, in the illustrated receiver now being described, the operation of the station-selector pushbuttons does not alter the position of the manual-tuning dial indicator. In the present example, the dial 68 reads 550 kc. but the receiver is actually tuned to 1400 kc., the frequency of the station associated with station-selector pushbutton 4.

When the operator presses manual-tuning pushbutton 6, the connection to ground of coil 48 of selector relay 36 is broken at the lower contacts of pushbutton 6, and selector relay 36 becomes inoperative until tuner-actuated switch 38 is operated at either the high-frequency or low-frequency limit of the tuner-core stroke, as will be described later. After depressing manual-tuning pushbutton 6, the operator turns the manual-tuning control knob in a clockwise direction to change the dial reading from 550 kc. to 900 kc., the frequency of the station he wants. In so doing, the operator increases the resonant frequency of the series-tuned circuit, comprising variable inductance 66 and capacitor 73, to the oscillator frequency corresponding to a station frequency of 900 kc. When the manual-tuning control knob is turned clockwise, the manually-operated reversing switch 69 associated therewith is moved to the right-hand position, unless already occupying that position. When selector relay 36 became inoperative, by reason of the connection to ground having been opened at the lower contacts of manual-tuning pushbutton 6, as previously described, the direction of rotation of motor 33 became governed by the position of manually-operated reversing switch 69, and not by the position of tuner-actuated reversing switch 37. When reversing switch 69 is in the right-hand position, the circuit is completed through the upper portion of field winding 47, and the motor turns in a direction to increase the frequency of oscillator 14. Observe then that in the present example, the frequency of the local oscillator is increased from that corresponding to a station frequency of 1400 kc., the station frequency of pushbutton 4, although the operator desires to select a station whose frequency is only 900 kc. The motor 33 continues to turn in the frequency-increasing direction until the cores of the tuner reach the upper-frequency limit of the core stroke at which time actuating-arms 52 and 54 engage switches 37 and 38. Switch 38 is momentarily grounded, thereby completing the circuit through coil 48 of selector relay 36, and the selector relay is energized by current from source 70 through the closed contacts of pushbutton 7 and switch 42 of control relay 35 which is in energized position since control tube 34 is conducting. When the movable contact-arms of selector relay 36 move to the energized or upper-contact position, a circuit to ground through the selector-relay coil 48 is completed by way of the selector relay's own switch-

contacts, i. e., switch 51, and relay 36 is held in energized condition. Switch 50, in energized position, connects the lower portion of field winding 47 to ground through tuner-actuated reversing switch 37, whose movable contact-arm is now in the right-hand position. And the movement of the arm of switch 49 of relay 36 to the energized position opens the circuit through the upper portion of field winding 47. The direction of rotation of motor 33 consequently reverses, and the motor now turns in a frequency-decreasing direction. Motor 33 continues to turn in the frequency-decreasing direction until the frequency of local oscillator 14 coincides substantially with the resonant frequency of the manually variable series-tuned circuit 66, 73. Tube 72 thereupon conducts and control tube 34 ceases to conduct, thus stopping the tuner motordrive and returning relays 35 and 36 to de-energized condition.

Assume that the operator now desires to manually tune in a station whose frequency is 750 kc., which is lower than the 900 kc. to which the receiver has just been tuned. To manually tune in a lower frequency station, the manual-tuning control knob is turned in a counter-clockwise direction. When this is done, reversing switch 69 is moved to the left-hand position, thus completing the circuit through the lower portion of field winding 47 by way of the lower contact of switch 50, relay 36 being in de-energized condition by reason of the depressed position of the "Manual" pushbutton 6 which opens the relay ground connection. Current through the lower portion of field winding 47 causes motor 33 to rotate in a frequency-decreasing direction.

Thus far, the operation of the improved tuning system has been described by a series of examples illustrating various operating conditions. As a result, general statements concerning the operation of the tuning system may now be made and clearly understood. It will be seen that the improved tuning system of the present invention utilizes a portion of the output of the local oscillator to control the motorized tuning of the receiver to a station selected at a remote point by either pushbutton or manual tuning means. The system is so constructed and arranged that the direction of rotation of the tuner motor is adequately controlled. When station-selector pushbutton tuning is being used, the direction of rotation of the tuner motor 33 is controlled by the position of the tuner-actuated reversing switch 37. When the receiver is manually tuned, as by means of a manual-tuning control knob (not shown), the direction of rotation of the tuner motor 33 is controlled by the position of the manually-operated reversing switch 69 associated with the manual-tuning control knob. A reversing-switch selector relay 36 selects the reversing switch which is to have control. During station-selector pushbutton operation, selector relay 36 is in energized condition; the manually-operated reversing switch 69 is then inoperative, and tuner-actuated reversing switch 37 is operative. During manual tuning, selector relay 36 is ordinarily in de-energized condition; manually-operated reversing switch 69 is then operative, and tuner-actuated reversing switch 37 is inoperative. When changing from station-selector pushbutton operation to manual tuning, the manually-operated reversing switch 69 controls the direction of rotation of the tuner motor except in the case where the operator rotates the manual-tuning control knob in one direction to move the dial toward a given frequency and the receiver is already, as a

result of pushbutton operation, tuned to a frequency which is in the opposite direction from that of the station desired. In that case, the manually-operated reversing switch 69 has initial control only, and, when the tuner cores reach the limit of the core stroke, the control of the direction of rotation of the tuner motor is taken away from manually-operated switch 69 and given to tuner-actuated switch 37 by the action of switch 38 and relay 36.

In the tuning system illustrated in the drawing, the receiver is muted whenever selector relay 36 is in energized condition, as is the case during station-selector pushbutton operation. The muting is accomplished by opening the speaker circuit at the lower contact of switch 51 of relay 36. When the selected station is tuned in, relay 36 is de-energized, as has been previously described, and the speaker circuit is reestablished.

An automobile broadcast receiver having a tuning system similar, except for the omission of automatic-frequency-control (AFC), to that illustrated in the drawing, and described above, has been built, installed and tested. The results obtained were very satisfactory, and the tuning was sharp and selective, even in the absence of automatic-frequency-control. The motordrive employed moved the tuner through the complete broadcast excursion in from three to four seconds.

I have described a preferred embodiment of my invention. Modifications may, of course, be made therein. For example, while I have described an inductance-tuned receiver, the tuning system of the invention may be employed to equal advantage in a capacitance-tuned receiver.

And while I have described motor 33 as being a reversible center-tapped shunt-wound D. C. motor, it will be understood that any suitable motor may be used. If the improved tuning system is employed in an A. C. receiver, the tuner motor will ordinarily be a reversible A. C. motor.

And while I prefer to use an evacuated tube for control tube 34, a grid-controlled gas tube may be employed, if desired, together with appropriate circuit modifications.

I have shown the biasing voltage for control tube 34 to be obtained from the biasing network of the receiver's push-pull amplifier. Any other suitable biasing circuit may, however, be used.

And while other biasing means may be used for detector triode 72, a particular advantage is obtained by using the biasing method shown in the illustration and described above. It will be understood that if the biasing voltage for detector tube 72 is too large, the tube will not conduct when local oscillator 14 reaches the resonant frequency of the selected tuned circuit, and motor 33 would, in that case, continue to run. On the other hand, if the biasing voltage is too small, the detector tube 72 will conduct over too wide a tuning range, and motor 33 may stop at a frequency not sufficiently close to the resonant frequency of the selected tuned circuit. When the biasing voltage is obtained in the manner illustrated and described, neither of the above unsatisfactory conditions will occur for the reason that the negative D. C. bias voltage and the R. F. oscillator voltage applied to the grid of tube 72 are maintained in substantially constant relationship. Consequently, if the frequency response of local oscillator 14 is not absolutely flat throughout the frequency band, the negative D. C. biasing voltage will vary in the same direction and in substantially the same proportion as the R. F. oscillator voltage

picked up by coil 28, thus insuring that current passes through the detector triode 72 only at substantially the resonant frequency of the selected tuned circuit and only at the positive peaks of the R. F. voltage of said resonant frequency.

Having described my invention, I claim:

1. In the tuning system of a superheterodyne radio receiver having a tunable local oscillator; a plurality of tuned circuits at least one of which is variable; means, including station-selector push-buttons and a manually operable tuning control, for selecting one of said tuned circuits; means for comparing the frequency of said local oscillator with the resonant frequency of said selected tuned circuit; means for deriving a voltage indicative of the relationship between said compared frequencies; and means for utilizing said derived voltage to change the frequency of said local oscillator in such direction and to such an extent that said local-oscillator frequency coincides substantially with the resonant frequency of said selected tuned circuit, said voltage-utilization means comprising a reversible motor mechanically coupled to said local oscillator and means for controlling the direction of rotation of said motor, said direction-controlling means including a tuner-actuated reversing switch to control the direction of rotation of said motor during station-selector pushbutton operation, a manually-operated reversing switch mechanically coupled with said manually-operable tuning control effective during manual tuning to effect rotation of said motor in the same sense as that in which said manually-operable tuning control is rotated, and a reversing-switch selector relay for selecting the reversing switch which is to have control of the direction of rotation of said motor, said selector relay being operative to take control away from the manually-operated reversing switch and to give control to the tuner-actuated reversing switch when, following station-selector pushbutton tuning, the manually-operable tuning control is turned in a sense opposite to that in which the motor should rotate to effect said coincidence between said local-oscillator frequency and said resonant frequency of said selected tuned circuit.

2. In the tuning system of a superheterodyne radio receiver having a permeability tuned local oscillator; a plurality of adjustable tuned circuits at least one of which is variable; means, including

station selector pushbuttons and a manually operable tuning control, for selecting one of said tuned circuits; means for comparing the frequency of said local oscillator with the resonant frequency of said selected tuned circuit; means for deriving a voltage indicative of the relationship between said compared frequencies; and means for utilizing said derived voltage to change the frequency of said local oscillator in such direction and to such an extent that said local-oscillator frequency coincides substantially with the resonant frequency of said selected tuned circuit, said voltage-utilization means comprising a vacuum-tube-controlled motordrive including a reversible motor mechanically coupled to said local oscillator and means for controlling the direction of rotation of said motor, said direction-controlling means including a tuner-actuated reversing switch to control the direction of rotation of said motor during station-selector pushbutton operation, a manually operated reversing switch mechanically coupled with said manually-operable tuning control effective during manual tuning to effect rotation of said motor in the same sense as that in which said manually-operable tuning control is rotated, and a reversing-switch selector relay for selecting the reversing switch which is to have control of the direction of rotation of said motor, said selector relay being operative to take control away from the manually-operated reversing switch and to give control to the tuner-actuated reversing switch when, following station-selector pushbutton tuning, the manually-operable tuning control is turned in a sense opposite to that in which the motor should rotate to effect said coincidence between said local-oscillator frequency and said resonant frequency of said selected tuned circuit.

FRANK HIMMER.
